UNITED STATES PATENT OFFICE.

HENRY E. GROSSENBACHER, OF OVERLAND, MISSOURI.

POULTRY-FEEDER.

1,187,905.

Specification of Letters Patent. Patented June 20, 1916.

Application filed July 15, 1915. Serial No. 40,008.

To all whom it may concern:

Be it known that I, HENRY E. GROSSEN-
BACHER, a citizen of the United States, re-
siding at Overland, in the county of St.
5 Louis and State of Missouri, have invented
certain new and useful Improvements in
Poultry-Feeders; and I do declare the fol-
lowing to be a full, clear, and exact descrip-
tion of the invention, such as will enable
10 others skilled in the art to which it apper-
tains to make and use the same.

My invention relates to useful improve-
ments in poultry feeding devices and has for
its object to improve upon the construction
15 of feeders of this class to such an extent as
to provide a device which although being
very simple and inexpensive, will be highly
efficient in operation and will possess a num-
ber of advantageous features, provision be-
20 ing made whereby the entire structure em-
ployed for supporting the feed hopper may
be knocked down at will.

With this general object in view, the in-
vention resides in certain novel features of
25 construction and in the unique combinations
of parts hereinafter fully claimed and de-
scribed by reference to the accompanying
drawings wherein,

Figure 1 is a front elevation of a feeder
30 constructed in accordance with my inven-
tion; Fig. 2 is a side elevation thereof; Figs.
3 and 4 are respectively vertical longitudi-
nal and vertical transverse sections; Fig. 5
is a horizontal section taken on the plane in-
35 dicated by the line 5—5 of Fig. 3; Fig. 6 is
a detail perspective view of the upper end of
one of the hollow standards and the stud
carried by the hopper for reception in said
end; Fig. 7 is an additional detail perspec-
40 tive of the intermediate portion of one
standard, and the co-acting end of the plat-
form supporting bar; and Fig. 8 is a detail
vertical section taken on the plane indicated
by the line 8—8 of Fig. 4.

45 In these drawings, which constitute a part
of the application and in which like refer-
ence characters designate corresponding
parts throughout the several views, the nu-
meral 1 indicates a pair of parallel horizon-
50 tally disposed feet preferably in the form
of sections of pipe of the required length.

The upper sides of the feet 1 are provided
therein with openings into which the lower
ends of a pair of substantially upright
standards 2 are inserted and held in posi- 55
tion by screw threads as shown in the draw-
ings, or by any preferred means.

The standards 2 are preferably formed
of pipes in order that the upper ends there-
of may receive studs 3 which depend from 60
a hopper 4 at diametrically opposite points,
said studs being here shown as formed by
reducing in width the lower ends of upright
plates 6 which are riveted, soldered, or
otherwise secured to the hopper. 65

The hopper 4 is provided with a funnel-
shaped bottom 6 having at its center a de-
livery opening 6' which is surrounded by a
depending annular flange 7, while the up-
per end of said hopper is closed by a conical 70
sheet metal cover 8 having in its apex an
opening which alines with an additional
opening in a horizontal plate 9 secured at
its ends to the under side of said cover.
Both of these openings receive therein the 75
upper end of an upright rod 10, this rod
being passed rotatably through upper and
lower horizontal bars 12 which are secured
at their ends respectively to the cylindrical
wall of the hopper 4 and to the funnel- 80
shaped bottom 6 thereof, said rod being pro-
vided with a stop nut 13 which overlies the
upper bar 12. The lower end of the rod 10
depends through the central opening 6', is
threaded, and receives a conical hub 14 85
which rises from the center of a horizontal
valve disk 15, the cone-shaped hub being
designed to extend substantially into the
opening 6' to control the discharge of feed
therethrough from the hopper, it being ob- 90
vious that said hub and the disk 15 may be
raised and lowered at will by proper adjust-
ment of the nut 13. Clamped on the lower
end of the rod 10 beneath the disk 15, by
a nut 17, is an additional and smaller disk 95
16 which is provided at its edge with a
downwardly and outwardly inclining rim
18 having an eccentric opening 19.

Received loosely in the opening 19, is an
upright crank arm 20 which rises from a 100
vertically oscillatory platform 21 mounted
between the standards 2, such platform be-

ing here shown as formed of a plurality of parallel longitudinal slats 22 connected at their ends by cleats 23 and secured at their centers to a horizontal bar 24 whose opposite ends are reduced in width to form bearing studs 25 which pass rotatably through openings 26 formed in the inner sides of the tubular standards 2. As shown at the left of Fig. 4, in Fig. 8 and in Fig. 7, one 10 of the bearing studs 25 is bent downwardly to provide a stop finger 27 which is disposed in one of the aforesaid standards, whereby when a predetermined amount of movement is imparted to the platform 21, said finger 15 will abut the standard and will prevent further movement.

In operation, an appropriate amount of grain is deposited in the hopper 4 and either 20 the nut 13 or the nut 17 is properly adjusted to allow an amount of such grain to be discharged through the opening 6' onto the edge portion of the disk 15, such portion now constituting a ledge for normally retaining a predetermined amount of feed. 25 When now, the fowls jump upon the platform 21 and oscillate the same vertically, the two disks 15 and 16, and the conical rim 18 will be oscillated horizontally through the instrumentality of the crank arm 20. This 30 movement of these parts, causes an amount of grain or other feed in the hopper to fall upon the aforesaid rim, from which it will drop to the earth, a slight amount remaining on the slats of the platform, this being 35 rather essential in order that it may serve as bait to cause the fowls to operate the device.

Although the feeder would operate to advantage comprising only the parts above described if it were employed only in poultry 40 houses or other shelters, it becomes highly essential to so construct the same as to permit its use out of doors regardless of the prevalence of rain and wind. To this end, an annular upstanding wind shield 28 surrounds the two disks 15 and 16 and the upper edge of the rim 19, said shield being secured to the bottom 5 of the hopper 4 and being necessarily spaced a distance from the edges of the disks, as shown clearly in Figs. 50 3 and 4. The shield 28 is not only advantageous for preventing the feed from being blown from the disk 15, but it serves to prevent rain water from running down the sides and bottom of the hopper and onto 55 the feed on said disk. Furthermore, the shield prevents sparrows and other predatory birds from stealing the feed.

When the devices are to be stored or shipped, they may be readily disassembled 60 by raising the hopper to such an extent as to withdraw the studs 3 from the tubular standards 2, and by shifting said standards laterally to disengage therefrom the bearing studs 25. If desired, the parts carried by 65 the lower end of the upright rod 10 may now

be detached and placed within the hopper. Thus it will be evident that the feeder will be compact and may thus be stored or packed in a comparatively small space. Another 70 advantage of the construction described, is that the hopper and parts carried thereby may be removed from the standards and carried to the granary to be refilled, this being a much easier task than the carrying of the entire device.

From the foregoing description, taken in connection with the accompanying drawings, it will be evident that although the construction of the device is very simple and therefore inexpensive, the same will be 80 highly efficient and durable and will possess a number of advantageous characteristics.

In the drawings, certain specific details of construction have been shown for accomplishing probably the best results, and in 85 the preceding such details have been described, but it is obvious that I need not be limited thereto otherwise than to the extent to which the appended claims restrict me.

I claim:—

1. A feeder comprising a hopper having a delivery opening in its lower end, a valve controlling the discharge of feed through said opening, a vertically oscillatory platform beneath the hopper, and a crank arm 95 rising from the platform to the valve member, whereby to actuate the latter upon oscillation of the former.

2. A feeder comprising a hopper having in its lower end an outlet, a horizontally oscillatory valve member controlling the discharge of feed through said outlet, said valve member being provided with an eccentrically disposed portion having therein an opening, a vertically oscillatory platform beneath the hopper, and a rigid crank arm 100 rising from said platform into the aforesaid opening.

3. A feeder comprising a supporting frame, a hopper supported thereby and movable vertically therefrom, said hopper having in its lower end an outlet, a horizontally oscillatory valve member controlling the discharge of feed through said outlet, said member having an eccentrically positioned 110 portion provided with an opening, a vertically oscillatory platform mounted on the frame, and a rigid crank rising from said platform removably into the aforesaid opening.

4. A feeder comprising a pair of upright standards having in their adjacent sides aligned openings, one of said standards being of tubular formation, a horizontal bar having its opposite ends provided with bearing studs projecting into said openings, a stop finger depending from one of the bearing studs into the tubular standard, a vertically oscillatory platform secured to the horizontal bar, a hopper supported by the stand- 120 130

ards and having in its lower end an outlet, a valve member controlling the discharge of feed from said outlet, and means having connection with the platform and the valve member for actuating the latter upon oscillation of the former.

5 In testimony whereof I have hereunto set

my hand in presence of two subscribing witnesses.

HENRY E. GROSSENBACHER.
